IGNITION DEVICE

Stanley M. Udale, Detroit, Mich., assignor to
George M. Holley and Earl Holley

Application January 12, 1949, Serial No. 70,529

4 Claims. (Cl. 123—117)

1

The object of this invention is to advance and to promptly retard the spark of an automobile engine as circumstances require, specifically to advance:

(a) When the speed increases at wide open throttle.

(b) When the throttle is only partly opened and the engine runs slowly.

(c) To retard the spark to its non-knocking position very quickly when the throttle is opened quickly at low engine speed. (To avoid the well known acceleration "knock".)

Fig. 1 shows the preferred form of my invention.

Fig. 2 shows the relationship between speed load and spark advance.

In the figures 10 is the air entrance of a conventional carburetor 12. 14 is the fuel nozzle discharging into the venturi 16, in the air entrance 10 of the main air passage 17. (There is 20 a low speed fuel outlet, not shown, discharging into the mixture outlet 19 and discharging adjacent the upstream lip of the butterfly throttle 32.) 18 is a passage leading out of the throat of the venturi 16 into a chamber 20. 22 is the first 25 moving wall or diaphragm forming the right hand wall of chamber 20. 24 is a second moving wall or diaphragm forming the right hand wall of chamber 26 which is connected through a pipe 28 with an opening 30 in the main air 30 passage 17, located above the atmospheric side of the lip of the carburetor throttle 32 when the carburetor throttle 32 is in its idle position.

A spark control rod 34 engages with plate 44 and is moved by two means:

(a) Directly by the diaphragm 22 to which it is connected positively, and

(b) Indirectly by a sleeve or tube 36 surrounding rod 34.

This sleeve 36 is provided with a short slot 37 so that it can pull the right hand end 38 of the rod 34 to the left but the rod 34 is free to be moved to the left by springs 46, 47 and plate 44, even though the tube 36 remains in the position shown. In other words the end of the rod 34, numbered 38, has a one way connection which projects through a slot in the sleeve 36, and engages with the circuit breaker plate 44. The tube 36 has a rod extension 40 which is engaged by a compression spring 42. This spring 42 engages at all times with the adjustable nut and washer 43 on the threaded rod 40. A stiffer, smaller and shorter spring 41 engages with the washer 43 after a limited movement of the diaphragm 24 to the left.

The length of the slot 37 is selected so that the left hand end of the slot 37, when the throttle 32 is wide open, engages with the projection 38 of the rod 34 so as to positively retard the spark partially during acceleration when the left hand end of the slot 37 engages with the projection 38.

The plate 44 is pulled clockwise by two springs 46 and 47, one of which is initially tight, the other one is loose. These three springs 42—46—47 control the position of the plate 44 at all times. At other times the fourth spring 41 also is active to control the advance. The reason one of these two springs 46—47 is loose is that one thus tightens up before the other. (See Westcott et al. case filed December 20, 1946, Serial No. 717,536, now Patent No. 2,503,645, issued April 11, 1950, and Colvin et al. case filed September 23, 1948, Serial No. 50,796, now Patent No. 2,557,527, issued June 19, 1951.) The plate 44 carries a circuit breaker arm 48 which engages with a stationary contact 49. The circuit breaker arm 48 is opened and closed by a cam 50, a finger 53, and a spring 52. An electrical connection 54 is provided for the low tension side of the coil (not shown).

The spring anchor pins 56—57 project through circular openings in the circuit breaker plate 44 to provide a maximum but limited advance of the spark determined by the clearance of the pins 56 and 57 in these openings.

Operation

The throttle 32 is shown in four positions. Position #1 (idle) is shown in full line, position #2 is shown during normal city driving, position #3 is wide open and position #4 is during normal country driving with the throttle almost wide open.

When moving from position 1 to position 2 the spark travels from A to F without much advance and then rises very rapidly to point G which is the maximum advance permitted by the openings in plate 44 surrounding the pins 56 and 57.

When the throttle stands in position 4 there is a slight suction in pipe 28, sufficient to overcome the relatively weak spring 42 but not enough to overcome the relatively stiff spring 41. The spark is now advanced along the line ADE. As the speed increases the depression in pipe 18 increases so that both diaphragms contribute to the advance. When the throttle is opened wide the suction in pipe 28 falls below that which can overcome the spring 42 and the only force advancing the spark is the Venturi suction transmitted through the pipe 18 to act on the diaphragm 22. The diaphragm 22 is then in the position shown, that is, in its extreme position over to the right when it is inoperative to advance the spark.

The slot 37 is of such a length that when accelerating by opening the throttle wide open the spark is positively knocked down from the horizontal line G to the horizontal line through C, that is, from 30° to 25°.

The curve AFGC from idle to ordinary road load is the normal spark advance. ABC is the normal spark for wide open throttle (position

#3) operation and a curve such as ADE is an intermediate spark advance curve when the throttle is not quite wide open (position #4).

The slight inflection in the line ABC at point B (800 R. P. M.) and in the line ADE at point D is caused by the springs 46 and 47 as set forth in the copending applications, Serial #717,536 Westcott et al. and Serial #50,796 Colvin et al.

The modification covered by these applications is the fact that one of the two springs 46 and 47 is loose so that the line AB rises at a more rapid rate than the line BC. If only one spring were used the inflection in the lines ABC and ADE would be reversed.

The modifications of this application are:

(a) The substitution of a short stiff inner spring 41 and a more flexible outer spring 42 for the single stiff spring of Serial #50,796.

(b) The short length of the slot 37 so that during acceleration the springs 41 and 42 positively knock the spark "down" to avoid making the engine knock.

If only one spring replaced the two springs 41 and 42 then when the throttle moved from its wide open position #3 to position #4 then the suction in venturi 16 would fall and the spark advance curve would fall below the line ABEC but the line ABEC is the lowest spark advance for good fuel economy.

Actually when the throttle moves from wide open to position #4 the spark should be advanced slightly (ADE). The smaller the engine the more important does this feature become, as the smaller engine operates more frequently with the throttle almost wide open than larger engines which operate either with the throttle open or closed. "Dynamic" suction describes the suction applied to the first moving wall 22. "Static" suction describes the suction applied to the second moving wall 24.

What I claim is:

1. An internal combustion engine ignition system comprising a main air passage for said engine, an air entrance thereto, a streamlined restriction in said entrance, an air outlet passage, a throttle valve therein, a first chamber, a first moving wall therein, a passage from said first chamber to the air entrance at the throat of said restriction, a second chamber, a second moving wall therein, a second passage from the air outlet passage at a point in said outlet where, when the throttle is closed, the passage is in communication with atmospheric pressure and as the throttle is opened it is gradually transferred to the suction on the engine side of said throttle, a spark timing advance plate, a circuit breaker mechanism mounted therein, two springs connected to said plate at one end, two fixed anchors connected to the other ends of said springs so that said springs oppose the movement of said plate in the spark advancing direction, one of said springs being made initially active to oppose the spark advance, the other having clearance so as to become active immediately after the plate begins to move away from its retarded position, a first rod connecting the first moving wall to said plate, a second rod connecting the second moving wall to said first rod through a one way connection, a third spring engaging with the second rod after the second rod has been moved by the two moving walls, a predetermined limited movement away from the extreme retarded position, a fourth control

when said second rod is in its extreme spark retarded position, said fourth control spring being relatively much weaker than said third control spring.

2. A device as set forth in claim 1 in which one end of the second rod is slotted to permit one end of the first rod to project through said slot to engage said plate so as to form said one way connection, said second rod is engaged by said fourth and third control springs and the slot is of such a length that when the throttle is suddenly opened wide during acceleration the escape of suction in the second chamber causes the second moving wall and the second control rod to move under the influence of the fourth and third control springs and to positively engage the first rod and to retard the spark by the impact of the second moving wall and second control rod on the first moving wall and first control rod and the plate connected thereto.

3. An ignition timing device for an internal combustion engine having a Venturi shaped air entrance and a throttle valve located downstream of said venturi and in which an engine driven cam operates a circuit breaker mounted on a movable plate the movement of which is responsive to the dynamic suction created by the air flow through said venturi and to the static suction created downstream of said throttle whenever the throttle is moved from its wide open position, the improvement which consists of a first chamber, a first moving wall therein, a passage from said first chamber to the venturi, a second chamber, a second moving wall therein, a second passage from the second chamber to a point that is transferred from the engine side of the throttle to the atmospheric side whenever the throttle approaches its closed position, a first link from the first moving wall to said movable plate, first yieldable means tending to rotate the plate in opposition to said dynamic suction, a second rod connected to said second moving wall, second yieldable means opposing the movement of said second moving wall in response to said static suction, said means being initially sufficiently weak to respond to the weak suction created by the initial closing motion of the throttle from its wide open position, a loose connection between the first and second rods to permit the first rod to act alone and to permit the second rod to assist the first rod to advance the timing whenever the static suction created by the initial movement of the throttle away from its wide open position becomes appreciable.

4. A device as set forth in claim 3 in which the second yieldable means comprises a variable yieldable means in which the initial resistance of said second yieldable means to static suction is relatively weak and after a relatively small movement of said second moving wall from its idle position, a relatively stiff yieldable means opposes the further movement of said second moving wall.
